UNITED STATES PATENT OFFICE.

ANTHONY J. CHRISTOPHER, OF BALDWINSVILLE, NEW YORK.

WIRES-FASTENING DEVICE.

1,307,240.

Specification of Letters Patent. Patented June 17, 1919.

Application filed January 15, 1919. Serial No. 271,234.

To all whom it may concern:

Be it known that I, ANTHONY J. CHRISTOPHER, a citizen of the United States, residing at Baldwinsville, in the county of Onondaga and State of New York, have invented new and useful Improvements in Wire-Fastening Devices, of which the following is a specification.

This invention relates to wire fastening devices the object in view being to produce a simple, reliable and practical device for fastening or securing in place wires and preferably insulated wires such as are used in alarm circuits and for other electrical connections, the device embodying construction by means of which a plurality of wires may be quickly fastened in fixed relation to a wall, post or other support and as quickly detached or unfastened when required.

With the above and other objects in view the invention consists in the novel construction, combination and arrangement herein fully described, illustrated and claimed.

25 In the accompanying drawings:—

Figure 1 is an elevation of the fastening device showing the clamping position of the same in relation to a plurality of wires.

Fig. 2 is a similar view showing the unclamping relation of the parts of the fastening device.

Fig. 3 is a plan view of the base member of the device.

Fig. 4 is a detail view of the movable clamping jaw of the device.

Fig. 5 is a detail view of the post.

Fig. 6 is a fragmentary section showing the relation between the post and the thumb piece or key.

40 Fig. 7 is a view of a modified form of base.

The wire fastening or clamping device consists of a base 1, a post 2, a movable clamping jaw 3, a thumb piece or key 4, and a jaw opening spring 5.

The base 1 is formed with holes 6 to receive suitable fastening devices such as nails or screws by means of which the device as a whole may be secured to a wall or partition or other light support. The base 1 is also formed with a square hole 7 in which one end of the post 2 is fastened permanently.

The post 2 is preferably square in cross section and is formed with a groove 8 around the outer end thereof to receive the thumb piece or key 4. The key 4 is formed with a socket 9 to receive the outer end of the post 2 in such manner that the key or thumb piece 4 has a swiveled connection with said post adapting said thumb post to be turned for a purpose which will appear.

The clamp 3 is formed with a square central hole 10 to receive the post 2 and enable the clamping member 3 to slide upon said post. At opposite sides of the hole 10, the clamping member 3 is formed with curved and substantially semi-circular portions 11 which partially embrace the wires shown at 12 and clamp the same firmly against the base 1.

The spring 5 which is of the compression type surrounds the post 2 between the base 1 and the clamping jaw 3 and serves to move the clamping jaw away from said base when the key or thumb piece 4 is turned in the proper direction.

The clamping position of the fastening device is illustrated in Fig. 1 wherein it will be seen that the wires 12 are held between the movable clamping jaw 3 and the fixed base 1, the wing portions of the thumb piece 4 bearing against the clamping jaw 3 at opposite sides of the center thereof. By giving the thumb piece 4 a quarter turn, in other words by turning said key from the position shown in Fig. 1 to the position shown in Fig. 2, the clamping member or jaw 3 is allowed to move away from the base 1, being actuated by the expansion of the spring 5. This enables the wires 12 to be easily and quickly removed from the clamping device. By reversing the operation just described, the wires may be again clamped in fixed relation to the device.

As shown in Fig. 7, the base 1' is provided with the curved recesses 1" for receiving the wires.

I claim:

A wire clamping device comprising a fixed base, a post extending from said base and non-circular shape in cross section, a clamping jaw slidable on said post and having an opening through which said post extends, said opening being of corresponding shape with said post in cross section, a com-

pression spring surrounding said post and interposed within said base and clamping member, and a thumb piece having a swivel connection with said post and adapted by a 5 quarter turn to press said clamping member toward the base or release the same, said

clamping member comprising curved portions at opposite sides of the center thereof which curved portions are adapted to partially embrace and hold a plurality of wires. 10

In testimony whereof I affix my signature.
ANTHONY J. CHRISTOPHER.
